[57] **CLAIM**

The ornamental design for a field terminated telecommunications connector panel, as shown as described.

DESCRIPTION

FIG. 1 shows a front elevation view of a first embodiment of my new design with the rear elevation view being a mirror image thereof;

FIG. 2 is view thereof;

FIG. 3 shows a left end view thereof with the right end view thereof being a mirror image of FIG. 3;

FIG. 4 shows a bottom plan view thereof;

FIG. 5 shows a cross-sectional elevational view thereof along the line 5—5 of FIG. 4;

FIG. 6 shows a front elevation view of a second embodiment of my new design with the rear elevation view being a mirror image thereof;

FIG. 7 shows a top plan view thereof;

FIG. 8 shows a left end view thereof with the right end view thereof being a mirror image of FIG. 8;

FIG. 9 shows a bottom plan view thereof;

FIG. 10 shows a cross-sectional elevation view thereof along the line 10—10 of FIG. 9;

FIG. 11 shows a front elevation view of a third embodiment of my new design with the rear elevation view being a mirror image thereof;

FIG. 12 shows a top plan view thereof;

FIG. 13 shows a left end view thereof with the right end view thereof being a mirror image of FIG. 13;

FIG. 14 shows a bottom plan view thereof; and,

FIG. 15 shows a cross-sectional elevation view thereof along the line 15—15 of FIG. 14.
